F. E. SEIFERT

LOCK WASHER

Filed Nov. 28, 1921

F.E. Seifert Inventor

By *Cal Snow Jr.*
Attorney

UNITED STATES PATENT OFFICE.

FRANK EMIL SEIFERT, OF SOMERVILLE, NEW JERSEY.

LOCK WASHER.

Application filed November 28, 1921. Serial No. 518,338.

To all whom it may concern:

Be it known that I, FRANK E. SEIFERT, a citizen of the United States, residing at Somerville, in the county of Somerset and State of New Jersey, have invented a new and useful Lock Washer, of which the following is a specification.

This invention relates to lock washers, the primary object of the invention being to provide a washer having means forming a part thereof for contacting with the nut or bar associated therewith, for locking the nut against movement.

Another object of the invention is to provide a washer of this character which will closely engage the article to which the same is applied, thereby preventing moisture entering under the washer.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a washer constructed in accordance with the present invention, and showing the same as applied to lock a nut.

Figure 2 is a plan view of the washer.

Referring to the drawing in detail, the reference character 5 designates a bar through which the bolt indicated at 6 extends, and to which bolt the nut 7 is secured.

The washer forming the essence of this invention is indicated at 8, and is shown as substantially frusto-conical in formation, tongues 9 being formed by stamping portions of the washer therefrom, and twisting the stamped portions upwardly to cause one of the respective corners thereof to bite into the nut 7 associated therewith, to prevent reverse movement of the nut.

It will be seen that when a nut is positioned over a washer of this character, the portion of the washer contacting with the bar 5 is embedded in the bar, and due to the close engagement between the bar and washer, all possibilities of moisture entering under the washer is eliminated.

Having thus described the invention, what is claimed as new is:—

A lock washer comprising in combination, a frusto-conical body portion, said body portion having slots formed transversely thereof, and having slots communicating with the transversely extending slots, the last mentioned slots extending in parallel relation with the periphery of the body portion, the sections of the body portion between the transverse slots being twisted to extend upwardly presenting piercing corners to engage a nut, and said piercing corners adapted to move over the contacting surface of a nut when the frusto-conical body portion is depressed.

In testimony that I claim the foregoing as my own, I have hereto affixed my signature in the presence of two witnesses.

FRANK EMIL SEIFERT.

Witnesses:

JOHN C. FOSTER,
JOHN J. DEGNAN.
